UNITED STATES PATENT OFFICE.

OSCAR RYAN, OF SIOUX CITY, IOWA.

DIAPHRAGM FOR TALKING-MACHINES.

1,364,890.

Specification of Letters Patent. Patented Jan. 11, 1921.

Application filed February 27, 1920. Serial No. 361,889.

To all whom it may concern:

Be it known that I, OSCAR RYAN, a citizen of the United States, and a resident of Sioux City, in the county of Woodbury and State of Iowa, have invented new and useful Improvements in Diaphragms for Talking-Machines, of which the following is a specification.

This invention relates to diaphragms for talking machines and the like and has particular reference to a fiber diaphragm and the process of making the same.

The primary object of this invention is to provide a diaphragm for talking machines and the like which will produce a clearer, louder and fuller tone than the diaphragms used in present day constructions. I am aware of the fact that diaphragms have been formed of bone, and materials other than the diaphragms used on popular makes of talking machines such as the Victor, Columbia and Edison but such diaphragms have not proven satisfactory in use, the tendency being to crack after a certain number of vibrations.

A further object of this invention is to provide a diaphragm for talking machines which is inexpensive to manufacture and strong, and durable in operation.

Other objects of the invention will be apparent during the course of the following description.

Referring to the drawings,

Figure 1 illustrates a perspective view of the material which forms a diaphragm, and,

Fig. 2 is a perspective view of the finished diaphragm.

In manufacturing the diaphragms which constitute my invention I first saturate several pieces of suitable paper in an exceedingly strong solution of zinc chlorid. These sheets of paper after being saturated are removed from the solution of zinc chlorid and superimposed one upon another and then passed through several series of compressing machines which may be coöperating rollers or the like and are gradually worked down until the excess solution of zinc chlorid has been forced out of the sheets. These rollers gradually compress the several thicknesses of paper into a thin compact mass.

It is to be understood that the above mentioned sheets are compressed through various series of rollers or the like until the desired thickness of the finished product is obtained.

Upon completion of the compression process this thin compact mass of fiber, as it may now be termed, is allowed to dry and after thoroughly drying, the surface of said mass is glazed by any suitable means. Upon experiment this completed article has been found to be exceptionally hard and without the disadvantage of brittleness of the present day diaphragms. After this fiber has been glazed as above described it is cut by any suitable means into the desired size required for operation with a talking machine and the opening in the center is formed by any suitable means.

From the above description it is obvious that I have provided a diaphragm possessing properties hereinbefore not present in the diaphragms in use and it is believed that the operation of this diaphragm will be readily understood by those skilled in the art to which it pertains.

Having thus described my invention, what I claim is new and desire to secure by Letters Patent of the United States is:

1. The process of forming talking machine diaphragms which consists of saturating a plurality of sheets of paper in a strong solution of zinc chlorid, superimposing the several sheets, one upon another, compressing the paper to expel the excess of zinc chlorid solution, drying the compressed mass, glazing the compressed mass, and cutting the mass into the desired size and shape. 90

2. A fiber diaphragm formed by saturating a plurality of sheets of paper in a strong solution of zinc chlorid, superimposing the several sheets, one upon another, compressing the paper to expel the excess zinc chlorid solution, drying the compressed mass, glazing the compressed mass, and cutting the mass into the desired size and shape. 95

3. A resonating flat fiber diaphragm comprising a plurality of superposed sheets of paper first treated with a solution of zinc chlorid and subsequently subjected to heat and pressure for compacting the mass. 100

OSCAR RYAN.
